STONEWORKING MACHINE

Filed Sept. 28, 1918

2 Sheets-Sheet 2

Fig. 3.

UNITED STATES PATENT OFFICE.

HENRY H. MERCER, OF CLAREMONT, NEW HAMPSHIRE, ASSIGNOR TO SULLIVAN MACHINERY COMPANY, A CORPORATION OF MASSACHUSETTS.

STONEWORKING MACHINES.

Application filed September 28, 1918. Serial No. 256,056.

To all whom it may concern:

Be it known that I, HENRY H. MERCER, a citizen of the United States, residing at Claremont, in the county of Sullivan and

5 State of New Hampshire, have invented certain new and useful Improvements in Stoneworking Machines, of which the following is a full, clear, and exact specification.

10 This invention relates to stone working machines, and more particularly to machines of the channeling type, the object of the present invention being to provide a simple but efficient apparatus mounted 15 on the channeler truck, and intended more particularly, though not exclusively, for the purpose of cutting the corner of a channel groove which extends under an overlying side wall or roof of a quarry, 20 or for cutting under any other conditions to which its particular construction is suited. A more specific object of the invention is to provide a simple mechanism for swinging the standard carrying the tools from a 25 vertical position to an inclined position, to provide means for securing the standard in a vertical or in an inclined adjusted position, and to so mount the standard swinging mechanism on the channeler truck 30 that the tools will make a continuous swinging cut as the channeler is fed under the roof or hanging wall.

The invention will be best understood by reference to the following description, when 35 taken in connection with the accompanying illustration, of a specific embodiment thereof, while its scope will be more particularly pointed out in the appended claims.

40 In the drawings,—

Fig. 1 is a front elevation of a channeling machine embodying one form of the invention.

Fig. 2 is a plan view of the guide and 45 bar.

Fig. 3 is a view on a smaller scale, showing the channeler in a different position when used for corner cutting.

Fig. 4 is a sectional view taken on line 50 4—4 of Fig. 1, the rotating parts being shown in elevation.

Referring to the drawings and to the machine shown therein, while the invention

may be embodied in machines and devices other than the specific type herein shown, 55 for the sake of illustration there is shown one embodiment of the invention in a track channeler of a general type extensively used, the same comprising suitable channeling mechanism mounted on the usual trunnion 60 bar 1, carried by a cross frame member 40 rigidly connected to journals 41, by means of which the truck body is mounted on axles carrying wheels 2, the latter being adapted to travel along a trackway 3 customarily laid on the quarry bottom. In accordance with the present invention, holes are bored in the web of the track rails for securing a rack 5 at different places along the rails, it being understood that this rack 70 may be dispensed with where the track is built with rails having a rack formed thereon.

The channeling mechanism, which may be mounted on either end of the trunnion bar, 75 comprises a standard 6 usually retained in adjusted position by one or more inclined braces. The standard is provided with suitable vertical guides 7 in which is mounted a sliding frame 8 carrying the cutting 80 mechanism, said sliding frame being vertically adjustable in said guides to move the cutting mechanism toward and away from the work by means of suitable feeding mechanism which forms no portion of the 85 present invention and which, being of usual construction, is not illustrated herein. The sliding frame is provided with vertical guides 9 in which is slidably mounted a crosshead 10 carrying a gang of channeling 90 tools 11.

The cross head and tools are reciprocated through suitable connections from a crank shaft 12 actuated by the usual motor, not shown. The connections between the crank 95 shaft and crosshead are such as to provide an elastic yielding medium between said parts, and to convert the rotary motion of the crank shaft into a movement of the tools which will cause them to perform their 100 functions in the most efficient manner. As herein shown, the crosshead is connected to a piston rod 13 secured to a piston, not shown, working in a cylinder 14 which is reciprocated in the sliding frame by a pitman 19 connecting it with the crank shaft 105

12, the frame for that purpose having secured thereto guides 15 which receive suitable slides 16 carried by the cylinder 14. A suitable guard plate 17, having an opening 18 to facilitate the inspection and oiling of the connection between the pitman 19 and crank pin, is fastened to the standard.

There is usually employed in machines of this type, an inclined brace, attached at its 10 upper end to the top of the standard, as at 20, and secured at its lower end to the trunnion bar, to retain the standard in a vertical position. In substitution for this usual brace, the present invention contemplates 15 the provision of a mechanism which will hold the standard in a vertical or inclined position or will swing the standard on a bearing, shown in dotted lines at 1', carried by the trunnion support, as the truck is 20 moved back and forth during the cutting operation. This mechanism comprises a double ended bracket or support 21, having clamping means 22 and 22' controlled by bolts 23, by which it is held to the trunnion 25 bar 1, the clamping means being disposed at an angle to each other so that either one or the other of the clamps may be bolted near one or the other end of the frame to hold a channelled guide and supporting member 24 at the required angle to the frame. The 30 clamps 22 and 22' are rigidly connected with the guides 24 by webs 25, and with each other by a web 25', as is shown in Figs. 1 and 4.

35 Sliding in and supported by the guide 24 is a bar 26 on the lower side of which are cast shrouded teeth 27, and on the upper side of which is a lug 28. The guide 24 is provided with a longitudinal slot 29 in 40 which the lug moves when the bar is given a reciprocating motion. A tie rod or brace 30 is connected by a bolt to the standard at 20 and by a yoke 31 and bolt 32 to the lug 28. The guide is split at both ends, as 45 shown at 33, so that the sides of the guide may be pressed toward each other to serve as a clamp to hold the bar 26 in different positions. Bolts 34 are provided for operating these clamps, the bolts passing through 50 holes formed in lugs on the under side of the guide. Nuts are threaded onto the ends of the bolts and may be tightened to give the necessary frictional engagement between the sides of the guide and the bar.

55 A driving pinion or cog wheel 35 is carried by one of the wheels 2 and is detachably held thereon by suitable means, as by bolts 36. Meshing with the cogs on the driving wheel 35, and also with the cogs 27 on the bar 26, is a cog wheel 37 held by a cotter pin 38 on a stud 39 carried by the web 25'.

When the channeling machine is being used in a vertical or adjusted position, the upper clamping means 33, 34 on the guide 60 is adjusted to grip the bar and thus make

a rigid brace extending from the frame to the top of the standard. During this operation, the rack 5 or driving wheel 35 is removed, so that there is no driving connection between the rails and the bar. If it is 70 desirable to break the driving connection for but a short time, the rack and driving gear are kept in place and the driving gear 37 is removed by pulling the cotter pin 38 and sliding the gear 37 off the stud 39. When it 75 is necessary to make a cut under an overhanging wall or roof, as illustrated in Fig. 3, a driving connection is made from the fixed rack 5 through the driving and driven gears 35, 37 to the bar 26. When the truck 80 is moved to the left, the bar 26 is forced to the right, so that the standard is swung about the axis of the pivot 1' in a plane extending longitudinally of the truck, carrying the tools 11 forwardly ahead of the 85 truck, and when the truck is moved to the right the standard is returned to an upright position.

If it is desired to tilt the standard backwardly transversely of the truck, as is found necessary in certain rock formations, the clamping bolts 23 are loosened, the standard is tilted on the trunnion bar 1 in the usual manner, and the bolts 23 are again tightened to hold the swinging mechanism in an inclined position. To allow for this relative movement of the gears, the teeth are so cut as to permit quite a little play between them, and the distance between the centers of rotation of the gears is made greater than is usual with gears of this type.

It will be observed that, by my improved channeler swinging mechanism, I have provided a simple, strong, and efficient means for swinging a channeler standard on its 105 trunnion support at any angle to the truck frame, that the moving parts are carried entirely by the frame, that readily accessible and easily operable means are provided for throwing the swinging means out of action, and that when the swinging means is inoperative to swing the channeler it may be used as a brace to hold the standard in any desired position.

While there is herein shown and described 115 for purposes of illustration one specific embodiment of my invention, it is to be understood that the latter is not limited to the details of construction herein shown, nor to the application of the invention herein illustrated, nor to the specific form of machine to which the same is shown as applied, but that extensive deviations may be made therefrom without departing from the spirit of the invention.

What I claim as new and desire to secure by Letters Patent is:

1. In a track channeler, the combination with a truck, and a tool pivoted on said truck, of means wholly carried by said truck 120

for swinging the tool by movement of the truck.

2. In a track channeler, the combination with a truck, truck running gear, and a tool, of self-contained means for swinging the tool actuated by the truck running gear.

3. In a track channeler, a truck, a tool pivoted thereon, and means for swinging the tool by movement of the truck including a

10 rack and pinion actuated by said movement.

4. In a track channeler, the combination with a track, a truck, truck wheels, and a tool, of means wholly carried by said truck for swinging the tool by movement of the

15 truck wheels.

5. In a track channeler, the combination with a track, a truck, truck wheels, and a tool adapted to swing in different planes, of means for swinging the tool by movement 20 of the truck, said means being adjustable to different angles to the truck and being wholly mounted thereon.

6. In a track channeler, the combination with a truck, a standard mounted on said truck, and a brace rod for said standard, of means connecting the truck running gear with the brace rod for swinging the standard.

7. In a track channeler, the combination 30 with a truck, a standard mounted on said truck, and a brace rod for said standard, of means connecting the truck running gear with the brace rod for swinging the standard, said standard and means being adjustable to different positions to adjust the plane of swinging movement.

8. In a track channeler, the combination with a track, a truck mounted on said track, a standard mounted on said truck, and a 40 brace rod for said standard, of rotative means contacting with said track and operatively connected to said brace rod for swinging the standard.

9. In a track channeler, the combination 45 with a truck, a standard mounted on said truck and a brace rod for said standard, of means operatively connecting the truck running gear with the brace rod to swing the standard.

50 10. In a track channeler, the combination with a track, a truck mounted on said track, a tool mounting pivoted on said truck and means actuated solely by the running gear of said truck for swinging the tool.

55 11. In a track channeler, the combination with a frame, a tool support, a tool mounted thereon, and a brace rod connected to said support, of means carried by said frame and having no connection external thereto and connected to said brace rod to swing the tool through the movement of the frame.

60 12. In a track channeler, the combination with a frame, a tool support, a tool mounted thereon, and a brace rod connected to said support, of self-contained means carried by

said frame and connected to said brace rod to swing the tool by movement of the frame.

13. In a track channeler, the combination including a truck, a swinging standard mounted on said truck, adjustable bracing 70 means for holding said standard in different positions, and means directly driven from the truck running gear for swinging the standard to said positions.

14. In a track channeler, the combination 75 with a frame, a tool support, a tool mounted thereon, and a brace rod connected to said support, of means carried wholly by said frame and connected to said brace rod to swing the tool through the movement of 80 the support, said means being adjustable to operate in different planes.

15. In a track channeler, in combination, a truck, a swinging standard thereon, means for bracing said standard against swinging 85 movement, said last named means combining brace means proper and means cooperating with said brace means to hold the latter immovable, said cooperating means being releasable, and means for moving said brace 90 means when said cooperating means is released.

16. In a track channeler, a standard constituting a support and guide for a channeling mechanism and having a pivotal 95 mounting, and means comprising an element having a single pivoted connection with said standard for adjusting and rigidly locking said standard at any position whatever within its range of pivotal movement. 100

17. In a track channeler, the combination including a truck, a swinging standard mounted on said truck, adjustable bracing means for holding said standard in different positions, and means independent from 105 said bracing means and acting directly thereon for swinging said standard to said positions.

18. In a track channeler, the combination including a truck, a swinging standard 110 mounted on said truck, bracing means adjustable to hold said standard in different positions, and means for adjusting one end of said bracing means in a direction making an angle with the length of said bracing means to cause the latter to move said standard to different positions.

19. In a track channeler, the combination including a truck, a swinging standard mounted on said truck, adjustable bracing 120 means for holding said standard in different positions, and means acting directly on said bracing means but forming no part thereof for swinging said standard to said positions, said last mentioned means being 125 located entirely on said truck.

20. In a track channeler, the combination including a truck, a swinging standard mounted on said truck, and means for swinging said standard during cutting 130

through different positions relative to said truck, said means comprising adjustable bracing means for rigidly holding said standard in any desired position whatever 5 within its range of movement.

21. In a track channeler, the combination including a truck, a swinging standard mounted on said truck, adjustable bracing means for holding said standard in different positions, and means acting directly on 10 said bracing means for swinging said standard through all said positions during cutting.

22. In a track channeler, the combination comprising a truck, a swinging standard mounted on said truck, adjustable bracing means for holding said standard in different positions, and means coacting with 15 said bracing means for swinging said standard 20 from one position to another during cutting.

23. In a track channeler, the combination with a truck, a standard adjustably mounted on said truck and a guide mounted on 25 said truck, of means carried by said guide and connected to said standard operative when held stationary in said guide to hold 30 said standard adjusted in fixed position, means for fixedly securing said first mentioned means in said guide, and means for adjusting said first mentioned means in 35 said guide to adjust said standard.

24. In a track channeler, the combination with a truck, a standard adjustably mounted 35 on said truck, a guide mounted on said truck, and a brace connected to said standard, of means carried by said guide and 40 pivotally connected to said brace for holding the standard in adjusted position, and 45 means for moving said last mentioned means in said guide to adjust the standard.

25. In a track channeler, the combination with a truck, a swinging standard mounted 45 on said truck, and a guide mounted on said truck, of means slideable relative to the 50 guide and operated by movement of the truck for swinging the standard.

26. In a track channeler, the combination with a truck, a swinging standard mounted 50 on said truck, and a support mounted on said truck in spaced relation thereto, of a movable member slideable in said support and operated by movement of the truck for 55 swinging the standard.

27. In a track channeler, the combination with a truck, a standard adjustably mounted 55 on said truck, a guide mounted on said truck, and a brace rod connected to said standard, of means reciprocable in said guide and connected to said brace rod for holding the 60 standard rigidly in adjusted position.

28. In a track channeler, the combination with a truck, a swinging standard mounted 65 on said truck, and a support mounted on

said truck in spaced relation thereto, of a 65 movable member reciprocable relative to said support and operated by movement of the truck for swinging the standard.

29. In a track channeler, the combination with a truck, a swinging standard on said 70 truck, and a support mounted on said truck, a movable member reciprocable relative to said support and operated by movement of the truck for swinging the standard, the support being adjustable to different angles 75 to the truck.

30. In combination, a frame, a swinging standard mounted thereon, a rigid member for supporting the frame, and means wholly carried by the frame and rotatably contacting with the member for automatically 80 swinging the standard on relative longitudinal movement between the frame and the member.

31. In combination, a frame, a standard 85 pivoted thereon, a rigid member relative to which said frame is movable, and rotating means carried by the frame and contacting with the member for transmitting a swinging movement to the standard.

32. In combination, a track, a movable frame mounted thereon, a swinging standard carried by said frame, and means carried wholly by the frame and having moving contact with the track for swinging the 95 standard.

33. In combination, a track having a serrated surface, a frame mounted thereon, a standard carried by said frame, and means mounted wholly on the frame and cooperating 100 with the serrated surface to swing the standard.

34. In a channeler, a movable frame, a swinging standard mounted thereon, a brace attached to said standard, and means attached to said brace and carried by said frame for swinging the standard or for holding it in different positions irrespective 105 of movement of the frame.

35. In a channeler, the combination comprising a rigid support, a rack attached thereto, a frame comprising wheels for supporting the frame on said rigid support, a swinging standard mounted on the frame, a cog wheel mounted on one of said wheels and 115 contacting with the rack, and means interposed between the cog wheel and the standard for swinging the standard.

36. In a channeler, a swinging standard, a brace attached to said standard, a bar 120 attached to said brace, and means for reciprocating said bar to swing said standard.

37. As an attachment for channelers having a frame, a swinging standard and a brace attached to said standard, a structure 125 including a guide member, two clamps attached to said guide member at equal angles thereto and adapted to secure said guide

- member to either end of said frame, and a bar sliding in said guide member and adapted for connection to said brace.
38. In a channeler, a swinging standard, a guide, clamping means on said guide, a bar mounted in said guide, a brace attached to said bar and said standard, and means for reciprocating said bar.
39. In a channeler attachment, two clamps connected by a web at an angle to each other, each of said clamps being adapted for attachment to one end of a channeler frame, a guide mounted on said clamps, and a rotating member mounted on said web.
40. In a channeler, the combination comprising a standard, a frame, a brace for connecting said standard and frame and comprising a guide clamped to the frame, a bar in said guide, means for connecting said bar and standard, and means carried by said guide for securing said bar in different positions.
41. In a channeler swinging mechanism, the combination comprising an axle, a frame mounted on said axle, a wheel carried by said axle, a guide member mounted on said frame, a bar movable in said guide, and means interposed between said wheel and said bar for moving said bar in said guide.
42. In combination, a frame, a standard mounted thereon, a sliding member carried by the frame and guided thereon for movement in a fixed path, a connection between the sliding member and the standard, and rotating means carried by the frame and contacting with the sliding member for moving the standard.
43. In combination, a track, a movable frame mounted thereon, a swinging standard carried by said frame, and means carried by the frame and contacting with the track at only one point to cause swinging of said standard.
44. In combination, a track, a movable frame mounted thereon, a swinging tool standard carried by said frame, and means for swinging the standard having only rotary contact with the track.
45. In combination, a track having a serrated surface, a frame movable therealong, a standard carried by the frame, and means mounted wholly on the frame and cooperating with the serrated surface to swing the standard.
46. In a channeler, a movable frame, a swinging standard mounted thereon, a brace attached to said standard, and means attached to said brace for swinging the standard when actuated by the movement of said frame, or for holding it at different positions.
47. In a channeler, a swinging standard, a brace attached to said standard, a bar attached to said brace, and means for longitudinally reciprocating said bar to swing said standard.
48. In a channeler, a truck, rolling running gear for said truck, a swinging standard mounted on said truck, and means for swinging said standard actuated directly by said rolling running gear.
49. In a track channeler, a track, a truck movable on said track, a driving wheel engaging said track for moving said truck, and a standard having a swinging mounting on said truck and connections between said driving wheel and said standard for swinging the standard.
50. In a track channeler, the combination with a track, a truck, truck wheels, and a tool, of means for swinging the tool by the rotary movement of the truck wheels.
51. In a track channeler, the combination with the track, a truck, truck wheels and a tool, of an operative connection between the tool and one of the truck wheels for swinging the tool.
52. In a track channeler, a truck, a standard pivotally mounted on the truck, and means for swinging said standard relative to said truck and carried by said truck, one element of the truck constituting both means operative to move the truck and a driving means for said standard swinging means.
53. In a track channeler, the combination with a truck, a standard adjustably mounted on said truck, a guide mounted on said truck and a brace connected to said standard, of means carried by said guide and connected to said brace for holding the standard in any position within its range of movement, and means for reciprocating said last mentioned means.
54. In a track channeler, the combination with a truck, a swinging standard mounted on said truck and a stationary guide mounted on said truck, of means carried by the guide and operated by movement of the truck for swinging the standard.
55. In a track channeler, the combination with a truck, a swinging standard mounted on said truck and a stationary support mounted on said truck in spaced relation thereto, of a movable member carried by said support and mounted thereon for motion of translation relative thereto and operated by movement of the truck for swinging the standard.
56. In combination, a frame, a swinging standard, a rigid member for supporting the frame, means carried by the frame for swinging the standard, and means likewise carried by the frame and having rolling contact with the first mentioned member for actuating said standard swinging means.
57. An attachment for channelers of the trunnion bar and pivoted tool standard type consisting of a guide, two clamps connected thereto by a web and at an angle to each

- other and to said guide, each of said clamps being adapted for attachment to one end of a trunnion bar, a bar adapted for pivotal connection to a standard to swing the same and slidably mounted in said guide, and a rotary member journaled on said web and having a driving connection with said bar, said rotary member being adapted to be actuated by said truck running gear.
- 10 58. An attachment for channelers of the trunnion bar and pivoted tool standard type, consisting of a guide, two clamps connected thereto by a web and at an angle to each

other and to said guide, each of said clamps being adapted for attachment to one end 15 of a trunnion bar, a bar adapted for pivotal connection to a standard to swing the same and slidably mounted in said guide, a detachably mounted rotary member journaled on said web and having a driving connection 20 with said bar, said rotary member adapted to be actuated by said truck running gear, and manually adjustable clamps for said bar at the ends of said guide.

In testimony whereof I affix my signature.
HENRY H. MERCER.
